ABSTRACT OF THE DISCLOSURE

Isolation from contaminants of a light modulating fluid layer on the rotatable disk of a light valve is achieved by use of a baffle plate spaced in close proximity to, and parallel to, the disk. Fresh filtered fluid dispensed from a channel of partially closed configuration on the side of the plate facing the disk maintains a fluid buffer region around the area of the disk whereon the fluid layer is to be deformed by an electron beam. The buffer region, contained between the plate and the disk, prevents contaminated, particulate-carrying sump fluid from reaching the disk surface.

Introduction

This invention relates to light valves for optical projection of images generated electronically on a fluid layer, and more particularly to a system for isolating from contaminated fluid the fluid layer upon which diffraction gratings corresponding to the images to be projected are formed.

One form of light valve suitable for optical projection of electronically generated images onto a remote display surface comprises an evacuated envelope containing an electron gun in alignment with a transparent disk. The disk is rotated through a reservoir of light modulating fluid to deposit a continuously replenished layer of fluid on the disk surface. An electron beam, generated by the electron gun, is directed through electrostatic beam deflecting and focusing means and is scanned across a portion of the light modulating fluid layer so as to selectively deform the layer. The fluid deformations thus formed constitute diffraction gratings which, in conjunction with a Schlieren optical system, selectively control passage of light from a light source through the disk and through an output window in the light valve envelope in order to create visible images at a remote display surface on which the light impinges.

Light valves of the type described have hitherto operated satisfactorily only for limited periods of time. Although the light modulating fluid is free from particulate contamination at the outset of light valve operation, a buildup of contamination occurs as operation of the light valve progresses. This contamination is due mainly to wear of moving parts within the light valve, as well as presence of impurities. In addition, some particles are formed as a result of massive damage to fluid molecules caused by heavy electron or ion bombardment. Eventually this contamination reaches a level which results in appearance of objectionable spots in the displayed image, since the particles present in the fluid tend to accumulate on the disk.

To overcome the problem of contamination, fluid filtering systems have been added to light valves. These systems permit flushing of the disks with fresh filtered fluid, thereby greatly extending the useful lifetimes of the disks. However, the flow rate of a flushing system is so high as to require a fluid reservoir, pump, and filter, all of large fluid-handling capacity. Consequently, at least a portion of the flushing system must be kept outside the envelope

2

in order to maintain the volume of the envelope within practical size; that is, within a size which does not require extraordinarily large envelope wall thicknesses and which, during fabrication of the light valve, permits pumpdown or evacuation of the envelope within a reasonable time.

The present invention concerns a light valve in which a portion of the disk rotates through a sump containing the light modulating fluid. Apparatus is provided for hydrodynamically isolating the light modulating fluid layer on the disk from the contaminated, particulate-carrying sump fluid in order to prevent the sump fluid from mixing with the fluid layer on the disk surface. By situating a baffle plate in close parallel proximity to the disk and dispensing fluid from a channel of predetermined configuration on the side of the baffle plate facing the disk, a low fluid flow rate is sufficient to maintain fresh filtered fluid within the entire region between the baffle plate and the disk. Only fresh filtered fluid is thus picked up by the disk even though the region between the baffle plate and the disk is situated within the sump.

Accordingly, one object of the invention is to provide a system for dispensing light modulating fluid in a light valve so as to require only a low volume filtering system for the fluid.

Another object is to provide apparatus for isolating the light modulating fluid layer on the surface of a rotating disk in a light valve from contaminated light modulating fluid.

Another object is to provide a light valve wherein the entire volume of light modulating fluid is maintained wholly within the light valve envelope.

Briefly, in accordance with a preferred embodiment of the invention, a light valve containing a rotatable disk, a layer of light modulating fluid coated on one surface of the disk, and a sump containing light modulating fluid are provided, with a portion of the disk being submerged in the sump. Apparatus for hydrodynamically isolating the light modulating fluid layer on the one surface of the disk from the contaminated fluid so as to prevent contaminated fluid from coating the one surface comprises a baffle plate spaced in close proximity to the one surface of the disk. The baffle plate is at least partially submerged in the sump and situated substantially parallel to the one surface of the disk. A fluid conveying means being open along its length is disposed in predetermined configuration on the side of the baffle plate facing the disk. Means coupled to the fluid conveying means are provided for furnishing fresh filtered fluid thereto.

Brief description of the drawings

The features of the invention believed to be novel are set forth with particularity in the appended claims. The invention itself, however, both as to organization and method of operation, together with further objects and advantages thereof, may best be understood by reference to the following description taken in conjunction with the accompanying drawings in which:

FIGURE 1 is a partially cutaway side view of a portion of a light valve showing the hydrodynamic contaminant isolation means of the instant invention; and

FIGURE 2 is a sectional view taken along line 2—2 in FIGURE 1.

Description of typical embodiments

FIGURE 1 illustrates a light valve containing the hydrodynamic contaminant isolation means of the instant invention. The light valve comprises an envelope 10, typically comprised of glass, containing a light output window portion 11 and a sump region 12 holding a reservoir of light modulating fluid 13. The interior of envelope 10 is evacuated to a low gas pressure.

The light modulating fluid is typically of the polybenzyltoluene type having a fluid viscosity of 1,000 centistokes at 60° C., with a vapor pressure in the range of 10⁻⁹–10⁻¹⁰ torr. The fluid contained in sump region 12 is that which has drained off an optically transparent disk 14 which is continuously rotated on bearings 15 about a shaft 16, typically at a speed in the order of 3 revolutions per hour. A spring 20 is maintained in compression by having its cap 21 affixed to a rigid support member 22 which, in turn, is affixed to envelope 10 of the light valve by any suitable means (not shown). The opposite end of spring 20 bears against the body of shaft 16. Consequently, a shoulder 23 on shaft 16 urges bearings 15 to force disk 14 against a plurality of protuberances 17, which may advantageously be formed of fritted glass droplets. These protuberances are affixed to output window 11.

Disk 14 is spaced apart from light output window 11 by a distance of about 3 mils so as to permit fluid 13 from sump 12 to rise by capillary action and fill the region between the disk and the output window. The 3 mil spacing is maintained by protuberances 17, as described in greater detail in H. E. Towlson Patent 3,385,991, issued May 28, 1968 and assigned to the instant assignee. As pointed out in the aforementioned Towlson patent, adverse effects produced by either a non-uniform fluid coating on the output surface of the rotatable disk, or by fluid condensate or droplets on the output window, are thereby eliminated.

A thin film 24, which comprises a transparent conductive coating such as indium oxide, is carried on rotating disk 14. Coating 24 may be maintained at any desired potential since a conductive path is formed through bearing 15, shaft 16, spring 20, cap 21 and member 22, permitting a continuous electrical connection to coating 24 through a stationary connection (not shown) which may be made to member 22. An aperture 19 in member 22 permits passage of an electron beam 25, originating at an electron gun 26, to be directed toward conductive coating 24 on disk 14. Disk 14 itself is non-conductive, and preferably is comprised of glass.

A thin film of light modulating fluid 27 is coated on thin film 24 and thus is situated in the direct path of electrons in electron beam 25. Beam 25 is focused and deflected by electron optical means (not shown) within the light valve and hence is swept, in raster fashion, over the surface of light modulating fluid layer 27. The pattern of charges on layer 27 produced by electron beam 25 causes corresponding deformations in the thickness of layer 27, resulting in formation of diffraction gratings 30. These gratings correspond to the image to be projected onto a remote display surface. Light from a light source (not shown) positioned behind electron gun 26 impinges upon a lenticular lens system 28 formed on the rear wall of envelope 10 and is directed by the lenticular lens system through aperture 19 onto diffraction gratings 30.

By modulation of electron beam 25 through application of suitable potentials to the electrostatic focus and deflection means, diffraction gratings 30 in fluid layer 27 are selectively controlled. Consequently, light passing through transparent rotatable disk 14 and output window 11 is selectively controlled and, in conjunction with externally located lenses of a Schlieren optical system (not shown) is projected on a remote display surface (not shown) to form an image representative of the intelligence modulating the electron beam.

A baffle plate 40, situated within sump 12, is spaced in close proximity to, and parallel to, disk 14. The spacing and orientation of baffle plate 40 with respect to disk 14 are maintained by spacer bars 41. By employing a metallic baffle plate, bars 41 may be welded to the baffle plate and mated with cavities 42 in output window 11. The baffle plate is then rigidly held in place by two spring clips 43.

The manner by which spring clips 43 hold baffle plate 40 to output window 11 is further illustrated in FIGURE

2, which is a sectional view taken along line 2—2 of FIGURE 1. In FIGURE 2 the width of baffle plate 40 can be seen to be larger than that of disk 14, while output window 11 can be seen to have protruding regions 47 which position bars 41 and clips 43 at locations to avoid interference with rotation of disk 14. Baffle plate 40 may alternatively be constructed of glass, in which case spacer bars 41 are likewise constructed of glass and joined by fritting to output window 11. Construction of this alternative type renders spring clips 43 unnecessary. The separation maintained between baffle plate 40 and disk 14, whether the baffle plate be constructed of metal or glass, is typically in the order of 10–15 mils.

Fluid conveying means 44 is disposed in predetermined configuration on the side of baffle plate 40 facing disk 14. This configuration is such as to permit flow of fresh filtered fluid outward in all directions parallel to the plane of disk 14, so as to maintain the entire region between disk 14 and output window 11 filled with fresh filtered fluid only. By continuing to supply fresh filtered fluid from a pump and filter 45, shown in FIGURE 1, through a closed tube 46 to fluid conveying means 44, fluid pressure in the region between baffle plate 40 and disk 14 is maintained sufficiently high to prevent contaminated fluid from sump 12 from entering this region. Accordingly, as disk 14 rotates, transparent coating 24 is continually covered with fresh filtered fluid only, since the surface of coating 24 does not contact any of the contaminated fluid in sump 12.

Fluid conveying means 44 preferably comprises an open channel recessed within the baffle plate so as to avoid any projecting surfaces on baffle plate 40 which might impede flow of fresh filtered fluid in any of the directions parallel to the plane of disk 14. This also helps to avoid turbulence in the outward flow of fluid from conveying means 44. Such turbulence could have the undesirable effect of mixing contaminated fluid from sump 12 with the fresh filtered fluid emerging from fluid conveying means 44, thereby adding contaminants to fluid layer 27.

The configuration of fluid conveying means 44 may conveniently be partially closed, such as arcuate, in form and situated within a volume adjacent to the area of disk 14, as shown in FIGURE 2. Accordingly, substantially the entire portion of the surface area of transparent conductive coating 24 submerged in fluid 13 is coated only with fresh filtered fluid.

A raster area 48 on oil film 27, which is the region upon which electron beam 25 may impinge to form diffraction gratings 30, is illustrated in its relative position on disk 14 in FIGURE 2. Although raster area 48 is shown as a discrete area, and is fixed with respect to output window 11, those skilled in the art will recognize that the raster area on disk 14 constitutes a circular band, due to the continuous rotation of the disk. Accordingly, with respect to disk 14, area 48 is merely an instantaneous region which conveniently aids in describing operation. It can be seen that with disk 14 rotating, as in the direction indicated by the arrow, instantaneous raster area 48 passes within close range of groove 44 for a period of roughly one-third of a revolution of disk 14. During this period, the instantaneous raster area is maintained in hydrodynamic isolation from contaminants contained in the sump fluid. During the remaining two-thirds of each revolution, the instantaneous raster area is outside the sump fluid.

By spacing baffle plate 40 at a distance of only 10–15 mils from disk 14, flow of fluid outward from fluid conveying means 44 provides twofold benefits. First, only a very small flow rate is required to maintain the entire submerged surface of transparent conductive coating 24 covered with only fresh filtered fluid. This is because the volume of fresh filtered fluid required to completely fill the region between baffle plate 40 and disk 14 is quite small. This low volume and low flow rate necessitate but a small fluid pump and small filter capacity, enabling the pump and filter to be situated within envelope 10 of the

light valve. The pump may be driven by a magnetic coupling (not shown) through glass envelope 10, so that no external mechanical connection need be made to the pump and filter. This reduces the requirements for glass-to-metal seals, thereby simplifying construction of the light valve. The action of the magnetic coupling on the pump of pump and filter means 45, moreover is such as to attract the pump tightly against envelope 10 at the region where the magnetic coupling is being made, so that no additional means are required to maintain pump and filter means 45 in proper position. The flow of fluid to and from pump and filter means 45 is indicated by the arrows in FIGURE 1.

The second benefit of closely spacing baffle plate 40 from disk 14 is that a laminar flow of fluid outward from fluid conveying means 44 is achieved. This flow is uniform over the entire length of fluid conveying means 44. The advantage of a uniform laminar flow is that turbulence is avoided and hence no mixing of the fresh filtered fluid with the contaminated fluid from sump 12 takes place within the region enclosed between disk 14 and baffle plate 40. This insures that only fresh filtered fluid can reach the surface of transparent conductive coating 24, so that spurious spots in the optically displayed image due to foreign particles in the diffraction gratings formed on oil film 27 are held to a minimum indefinitely.

The fluid flowing at the low rate, which is in the order of 3 cubic centimeters per minute, is distributed by making groove 44 in the order of 100 mils wide, although the groove may be made as wide as $\frac{1}{4}$ inch without detriment to the laminar flow therefrom. The cross-sectional configuration of groove 44 may conveniently be rectangular and, for a groove of about 50 mils in depth, a metallic baffle plate of approximately $\frac{1}{16}$ inch thickness may be utilized.

The foregoing describes a low volume filtering system for the light modulating fluid of a light valve. The filtering system is contained entirely within the light valve, and is capable of withstanding a 450° C. bake in air, followed by a 400° C. bake in vacuum, both of which are typically employed in fabrication of the light valve in which the invention is utilized. The entire volume of light modulating fluid is maintained wholly within the light valve envelope. Apparatus is provided for isolating from contaminated light modulating fluid the light modulating fluid layer on the conductively-coated surface of the rotating disk of a light valve.

While only certain preferred features of the invention have been shown by way of illustration, many modifications and changes will occur to those skilled in the art. It is, therefore, to be understood that the appended claims are intended to cover all such modifications and changes as fall within the true spirit of the invention.

I claim:

1. In a light valve containing a rotatable disk, a layer of light modulating fluid coated on one surface of said disk, and a sump containing contaminated light modulating fluid, a portion of said disk being submerged in said sump, apparatus for hydrodynamically isolating the light modulating fluid layer on said one surface from said contaminated fluid so as to prevent contaminated fluid from coating said one surface, said apparatus comprising:

- means immersed in said sump and situated in close proximity to said one surface of said disk so as to define a predetermined volume of fluid adjacent said one surface of said one surface of said disk; means communicating with said volume and furnishing fresh filtered fluid thereto at a flow rate sufficiently high to prevent any of said contaminated fluid from entering said volume.
2. The apparatus of claim 1 wherein said means communicating with said volume includes an open channel situated within said sump and producing a laminar flow of fluid from the entire open portion of said channel.
3. In a light valve containing a rotatable disk, a layer of light modulating fluid coated on one surface of said disk, and a sump containing contaminated light modulating fluid, a portion of said disk being submerged in said sump, apparatus for hydrodynamically isolating the light modulating fluid layer on said one surface from said contaminated fluid so as to prevent contaminated fluid from coating said one surface, said apparatus comprising:
- a baffle plate spaced in close proximity to said one surface of said disk, said baffle plate being at least partially submerged in said sump and situated substantially parallel to said one surface of said disk; fluid conveying means disposed in predetermined configuration on the side of said baffle plate facing said disk, said fluid conveying means being open along its length; and means coupled to said fluid conveying means for furnishing fresh filtered fluid thereto.
4. The apparatus of claim 3 wherein said fluid conveying means comprises an open channel recessed within said baffle plate.
5. The apparatus of claim 3 wherein said means furnishing fresh filtered fluid to said conveying means comprises a fluid circuit communicating with said sump for removing contaminated fluid from said sump, said fluid circuit including fluid filtering means and fluid pumping means so as to filter fluid removed from said sump and furnish the filtered fluid to said conveying means.
6. The apparatus of claim 5 wherein said fluid conveying means comprises an open channel recessed within said baffle plate.
7. The apparatus of claim 5 wherein said fluid circuit is wholly contained within said light valve.
8. The apparatus of claim 6 wherein said fluid circuit is wholly contained within said light valve.
9. The apparatus of claim 6 wherein the predetermined configuration of said open channel is generally arcuate.
